LOCK

Luis Alberti, Buenos Aires, Argentina

Application July 2, 1934, Serial No. 733,514

2 Claims. (Cl. 70—47)

This invention refers to locks, both for room doors and the like which are actuated indifferently from either side of the door and for doors of closets, safeboxes and the like which are actuated from only one side. This new lock is simple in construction, operates easily and provides substantially an absolute safeguard against violation.

The invention is illustrated in the accompanying drawing, in which—

10 Figure 1 is a view, partly in section and partly in elevation, of a lock having the invention applied thereto.

Figure 2 is a section on the line 2—2 of Figure 1.

15 Figure 3 is an enlarged longitudinal section through the locking mechanism of the invention.

Figure 4 is a detail view similar to Figure 3 and showing a different position of the parts at the inner end of the lock.

20 Referring in detail to the drawing, 1 is the key, 2 is the exterior handle, of any approved form, of a roll-back shaft 3 which passes through the whole locking mechanism and which at its interior end, is provided with a roll-back arm 12 which actuates the lock bolt 13.

The lock includes a metal block 4 which is preferably circular in cross section and has an opening extending from end to end thereof through its upper portion and in which the roll-back shaft 3 is mounted to rock or rotate. The roll-back shaft has a circumferential notch or socket 5 at or near its inner or rear end and contains a plurality of radial perforations 6.

These perforations 6 are continued along both sides of the roll-back shaft into the block 4, so that they form complete channels which extend from one side of the block 4, through the bar 3, to end at the other side of the block 4 where will be found the open longitudinal space or key slot 7, provided for the introduction of the key 1.

At the end which is most remote from the open longitudinal key slot 7, each perforation houses a spring 8 bearing upon a pin segment 9 which, when spring 8 is closed, will reach exactly to the part crossed by the roll-back shaft 3. The part of the perforation which passes through the roll-back shaft 3, contains a pin segment 10, and a third pin segment 11 occupies the rest of the perforation, viz. the portion between the roll-back shaft 3 and the open longitudinal space or keyhole 7. The latter segments 11 are of different lengths relative to the perforation which they respectively occupy between the roll-back shaft 3 and the open longitudinal space or keyhole 7, and the walls of this space or key slot are

grooved or ribbed longitudinally to correspond to the cross section of the key and the edge of the key is serrated or notched to present an outline mating with the outline presented by the projecting ends of the series of pins.

As will be understood, when the key 1 is withdrawn from the keyhole 7, there is a cessation of the pressure which said key exerted through the pin segments 9, 10, 11 upon the springs 8. Springs 8, therefore, will now push pin segments 9 towards 10 the open longitudinal space or keyhole 7, causing them to enter partially into the perforations of the roll-back shaft which up to now had been occupied solely by segments 10, and causing the pin segments 10 to enter partially into the continuations of said perforations in block 4, the pin segments 11 in turn being projected partially into the key slot 7. As the ends of the pin segments are now no longer in line with the circumference of the roll-back shaft 3, the bar will be held 20 against turning and the lock cannot be opened.

When the key is again inserted in the key slot, the pin segments 11 will be pushed back into the interior of the perforations, they will push upwards the segments 10 and these in turn will push 25 segments 9; these latter segments finally will press against springs 8 and the ends of the segments again will be in line with the circumference of the roll-back shaft 3 which thus will be enabled to turn.

30 However, the alignment of pin segments 9, 10, 11 with the roll-back shaft will not alone permit rotary movement of the bar. There is still another safety device which impedes it. Indeed, it was said before that the roll-back shaft 3 has a 35 groove 5, and in passing also may be mentioned set screw 23 which is mounted in the upper portion of the block 4 and projects into another annular groove 24 on the roll-back shaft 3 with the purpose of safeguarding the shaft 3 against 40 movements in a longitudinal direction. Groove or socket 5 forms only a hole which is aligned with a groove or recess in the block in which is slidably mounted a pin 20 beneath which is a spring 21, and near its lower end a recess or notch 22 is 45 formed in the pin 20 to be engaged by the tapered point of the key. Normally, when the key is not in the lock, the head or superior end of pin 20 enters into groove 5 of the roll-back shaft 3, as spring 21 pushes pin 20 upwards. In this position, the recess 22 remains so high that, when the key arrives at the pin, its point touches the lowest part of the recess, and as the key progresses, the inclined edge face of its point draws pin 20 downwards, withdrawing its head from 55

socket 5 of roll-back shaft 3. It is, therefore, necessary that the point of key 1 enters into recess 22 of pin 20, so as to exercise a pressure which acts upon spring 21 and produces the descent of pin 20, the head of which is thus withdrawn from the socket 5, placing the roll-back shaft 3 into condition to turn. This construction offers an important additional device to augment the security of the lock.

As will have been seen, the purpose of key 1 is only to enable, by means of its introduction into keyhole 7, the roll-back shaft 3 to turn, whereas the key itself remains stationary. After inserting the key, a rotary movement can be given to the roll-back shaft 3 by means of its handle 2, whereby arm 12 provided at the interior end of the roll-back shaft 3 will turn also. During its rotary or rocking movement the roll-back arm 12 will lift the tumbler 14 against the force of a spring 15 which bears upon the upper edge of the tumbler to yieldably hold it in its lowered normal position. The arm 12 then engages a notch 16 in the upper wall of an opening or slot in the bolt 13 so as to partly retract the bolt, and during a second revolution the arm 12 will engage a second notch 17 in said wall, thereby fully retracting the bolt so that the door may be opened. These notches 16 and 17 of the lock bolt 3 and cooperating elements are in double systems, used for room doors and others which are to be actuated indifferently from one side or the other, within reach of the roll-back arm 12 of each one of the two mechanisms, and this will be seen when looking at Figure 2 where lock bolt 13 occupies the central part flanked by the two mechanisms which, on doors which are to be actuated from one side only, will be reduced to one mechanism; as will be understood.

The door may be provided with the usual latch bolt indicated at 18.

Although the locking device has been described and illustrated particularly with reference to room doors actuated from both sides, it is to be understood that the invention is not limited to this use which has been chosen to show the device

in its most complicated form. The device, in a more primitive form of construction, viz.: using a single mechanism, can be employed for all kinds of closure devices, wherever fastening means are to be applied. The invention can be used for 5 padlocks, for fastening motor cars, the curtains of show-windows, closure doors of closets, safe boxes and, finally, all objects, doors or openings which are to be locked by means of a locking system.

What I claim as my invention, and desire to 10 secure by Letters Patent, is as follows:

1. A locking device comprising a block having an opening extending through its upper portion from end to end thereof and a key slot in its lower portion parallel with said opening, a roll-back shaft mounted in said opening and having a 15 socket in its circumferential surface at its inner end, tripartite pins mounted in the block and the shaft and operable by an inserted key, a latch bolt slidably mounted in the block at the inner 20 end thereof to engage the socket in the shaft, said latch bolt having a recess in its lower portion presented to the key slot, and yieldable means for holding said latch bolt in an upper position, the recess being engaged by the tapered end of an 25 inserted key to draw the latch bolt from the shaft.

2. A locking device comprising a block having an opening formed therethrough and a key slot parallel with said opening, a roll-back shaft 30 mounted in said opening and adjacent its inner end having a socket in its circumferential surface, tripartite pins mounted in the block and the shaft and operable by an inserted key, a latch bolt slidably mounted in the block and movable 35 radially of the shaft into and out of position to engage in the socket in the shaft, said latch bolt having a seat presented to the key slot and formed with a cam surface, and yieldable means for holding said latch bolt in position to enter the socket 40 of the shaft, the cam surface being engaged by the end of the inserted key to move the latch bolt away from the shaft.
